(57) CLAIM

The ornamental design for a packaging, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a first embodiment of the packaging;

FIG. 2 is a front plan view thereof;

FIG. 3 is a back plan view thereof;

FIG. 4 is a top plan view thereof;

FIG. 5 is a bottom plan view thereof;

FIG. 6 is a left side plan view thereof;

FIG. 7 is a right side plan view thereof;

FIG. 8 is a zoomed-in view of a portion of the top plan view shown in FIG. 4;

FIG. 9 is a perspective view of a second embodiment of the packaging;

FIG. 10 is a front plan view thereof;

FIG. 11 is a back plan view thereof;

FIG. 12 is a top plan view thereof;

FIG. 13 is a bottom plan view thereof;

FIG. 14 is a left side plan view thereof;

FIG. 15 is a right side plan view thereof; and,

FIG. 16 is a zoomed-in view of a portion of the top plan view shown in FIG. 12.

The broken lines showing in the drawings are for the purpose of illustrating environmental structure and form no part of the claimed design.

The trademark LOFRIC Hydro-Kit forming part of the claimed design is a registered trademark of Dentsply IH AB. The trademark WELLSPECT forming part of the claimed design is a registered trademark of Dentsply Sirona Inc. (the parent company for applicant Dentsply IH AB).
